ANTENNA

Salvator Baldi, New York, N. Y.

Application April 18, 1949, Serial No. 2,101

Term of patent 3½ years

(Cl. D26—14)

To all whom it may concern:

Be it known that I, Salvator Baldi, a citizen of the United States of America, residing in New York city, county of New York, and State of New York, have invented a new, original, and ornamental Design for an Antenna, of which the following is a specification, reference being had to the accompanying drawing, forming part thereof, wherein,

Figure 1 is a front perspective view of an antenna showing my new design with the antenna conductors positioned upright.

Figure 2 is a front elevational view of the antenna shown in Figure 1, drawn on a smaller scale, showing the antenna conductors positioned substantially horizontal, and showing said conductors in slightly extended position.

I claim:

The ornamental design for an antenna, substantially as shown and described.

SALVATOR BALDI.
